UNITED STATES PATENT OFFICE.

CHARLES T. STUKENBERG, OF ALBERS, ILLINOIS.

CABINET.

1,316,118.

Specification of Letters Patent. Patented Sept. 16, 1919.

Application filed September 11, 1918. Serial No. 253,516.

To all whom it may concern:

Be it known that I, CHARLES T. STUKENBERG, a citizen of the United States, residing at Albers, in the county of Clinton and State 5 of Illinois, have invented certain new and useful Improvements in Cabinets, of which the following is a specification.

This invention relates to cabinets and more particularly to a coal cabinet.

10 The primary object of this invention resides in the provision of a cabinet in which a supply of coal may be stored in the kitchen of a residence to eliminate the usual inconvenience of conveying coal from the coal bin 15 to the stove in small quantities.

Another object of this invention resides in the provision of a cabinet from which the coal stored therein may be readily shoveled therefrom in the desired quantities 20 ties without creating dust or the like.

A still further object of this invention resides in the provision of a coal cabinet for storing the coal adjacent the stove in such a manner that the amount on hand will be 25 readily seen without lifting the cover to the cabinet.

With these and other objects in view this invention resides in the provision of certain novel features of construction, arrangement of parts and combination of elements 30 to be more fully set forth in the following specification and it is to be understood that minor changes in detail may be resorted to as come within the spirit of the appended 35 claims.

In the accompanying drawing:

Figure 1 is a perspective view of the cabinet,

40 Fig. 2 is a central vertical sectional view of the same.

In the present embodiment of this invention the numeral 5 indicates the cabinet which consists of a rear wall 6 and side walls 7. This cabinet while herein shown as being 45 constructed of wood may be manufactured from any suitable material and in various sizes.

The front of this cabinet consists of a rearwardly and downwardly inclined wall 50 8 and a substantially perpendicularly arranged wall 9 in which is cut an access opening 10 for access to the coal.

The bottom 11 of this cabinet projects forwardly of the side walls 7 and is inclined rearwardly in order that the coal will not 55 fall through the opening 10 when the cabinet is filled and for the purpose of piling it at the rear of the cabinet when a small quantity is in the cabinet.

In order to ascertain when the cabinet is 60 about empty an upwardly directed wire net 12 is fastened in any suitable manner to the top of the wall 9 and bottom of the wall 8.

The cabinet is provided with a stationary 65 top 13 to which is hinged as at 14 a cover 15 for filling the cabinet with a quantity of coal.

Fastened in any suitable manner to the top of the cabinet is a series of shelves 16 in 70 order that kitchen utensils or the like may be placed thereon.

Thus having fully described this invention, it is apparent that a cabinet has been produced which not only reduces the labor 75 of conveying the coal from the bin but through its adoption a sanitary cabinet of convenience is presented at a nominal expense.

What I claim is:

1. A cabinet of the character described comprising a rear wall, an inclined bottom, side walls, a vertical wall resting on said bottom with an opening therein, an inclined front wall above said vertical wall with its 85 lower edge disposed inwardly of the upper edge of said vertical wall, and a wire net connecting the lower edge of the front inclined wall and the upper edge of the front vertical wall, all arranged as set forth. 90

2. A coal cabinet comprising a rear wall, side walls, a bottom, a depending front wall, an upstanding front wall, said front walls being so arranged with respect to each other as to provide an opening through which the 95 coal in the cabinet may be seen, and a wire screen closing such opening.

In testimony whereof I affix my signature in the presence of two witnesses.

CHARLES T. STUKENBERG.
